UNITED STATES PATENT OFFICE.

MOSES L. HAWKS, OF NEW YORK, N. Y.

SHARPENING DEVICE.

1,168,302.

Specification of Letters Patent. Patented Jan. 18, 1916.

Application filed July 21, 1915. Serial No. 41,179.

To all whom it may concern:

Be it known that I, MOSES L. HAWKS, a citizen of the United States, residing at New York city, in the county of New York and State of New York, have invented a new and useful Sharpening Device, of which the following is a specification.

The principal object of the present invention is to provide a simple, efficient and inexpensive sharpener for home use in sharpening knives and scissors such as are in general use for domestic purposes, and a sharpener that requires but little skill or experience to operate, also having the proper facilities and means for sharpening the knives on both sides of the blade at the same time whereby a saving of time is effected and a more uniform surface, and a more perfect cutting edge is imparted to the knife. I attain these objects by the mechanism illustrated in the accompanying drawings in which—

Figure 1 is a plan view of the finished sharpener, Fig. 2 is a longitudinal half section of Fig. 1, Fig. 3 is a transverse sectional view on the line $x-x$ of Fig. 1 and Fig. 4 shows the blank from which the two sharpening members are made.

Preferably the two sharpening members are made from sheet steel by means of blanking and forming dies after which the beveled marginal circumference of each member is provided with file cut sharpening teeth 2 and properly hardened for the purpose, the two sharpening members are then tightly clamped together between the ends of the handles or parts that serve as handles in operating the device and which may be joined by means of a double pointed screw as shown in Fig. 2 of the drawings, or the same may be joined by means of a rod or bolt permanently secured in one of the handle portions and the projecting end either screwed or driven into the other until the two sharpening members are clamped together as shown, at least one of the sharpening members is provided with one or more short radial projections, preferably two in number, as shown at 3, Figs. 2 and 3, and which are bent or turned outward to form bearings for the blades of scissors or shears while being sharpened.

It will be observed that when the two sharpening members are clamped together as shown the beveled sharpening surfaces

form a groove in which the knife is drawn and by means of which both sides of the blade of the knife are brought in contact with the cutting teeth of the sharpening members at the same time during the sharpening operation and thus the knife is speedily and thoroughly sharpened requiring but little skill or effort to accomplish.

Scissors or shears are readily sharpened by holding the flat side of the blade on one of the bearings 3, which will bring the beveled edge of the shear to bear on the cutting teeth of the opposite sharpening member, the shear being drawn from heel to point across the sharpening surface which speedily sharpens the shears.

In the construction and disposition of the several parts in relation to each other, it will be seen that I have devised and provided a very simple, efficient and inexpensive knife and scissor sharpener that is adequate and well adapted to general domestic use.

What I claim as my invention and desire to secure by Letters Patent is—

1. A sharpening device consisting of two centrally perforated sharpening members blanked and formed as described, having a beveled marginal surface on which are file cut sharpening teeth, the beveled sharpening surface of said members forming a groove for the blade of a knife when the two members are clamped together as shown, the said sharpening members being tightly clamped together between the ends of the handles or parts serving as a handle for same.

2. A knife and scissor sharpener consisting of two centrally perforated sharpening members circular shaped in their general contour and having a beveled marginal surface on which are file cut sharpening teeth, the beveled sharpening surface of said members forming a groove for a knife blade when the two members are clamped together as shown, at least one of the sharpening members being provided with one or more radial projections bent or turned outward at a more obtuse angle than that of the beveled sharpening surface so as to form a bearing suitable as a guide in sharpening scissors or shears, the said sharpening members being firmly clamped together between the ends of the handles or parts serving as a handle for same.

MOSES L. HAWKS.
